[57] CLAIM

The ornamental design for a railing, shown and described.

DESCRIPTION

FIG. 1 is a fragmentary right side elevational view of a railing showing my new design, the broken lines showing the ends of the railing and partial banisters are for illustrative purposes only and form no part of the claimed design;

FIG. 2 is a fragmentary top plan view thereof;

FIG. 3 is a fragmentary left side elevational view thereof;

FIG. 4 is a fragmentary bottom plan view thereof; and,

FIG. 5 is an end elevational view the opposite end being identical thereto, the railing is of constant cross-section throughout its length.
